UNITED STATES PATENT OFFICE

CAROLUS L. EKSERGIAN AND TALMON A. DAVENPORT, OF DETROIT, MICHIGAN, AS-SIGNORS TO BUDD WHEEL COMPANY, OF PHILADELPHIA, PENNSYLVANIA, A CORPORATION OF PENNSYLVANIA

DESIGN FOR AN ARTILLERY WHEEL

Application filed April 4, 1932. Serial No. 43,394. Term of patent 14 years.

To all whom it may concern:

Be it known that we, CAROLUS L. EKSERGIAN and TALMON A. DAVENPORT, citizens of the United States, residing at Detroit, in the county of Wayne, and State of Michigan, have invented a new, original, and ornamental Design for an Artillery Wheel, of which the following is a specification, reference being had to the accompanying drawing, which forms a part hereof.

Figure 1 is a side elevation of a wheel made in accordance with our novel design.

Figure 2 is a perspective view.

Figure 3 is a transverse spoke section.

Figure 4 is an axial profile view of our design.

We claim:

The ornamental design for an artillery wheel as shown.

Signed at Detroit, county of Wayne, State of Michigan, this 29th day of March, 1932.

CAROLUS L. EKSERGIAN.

TALMON A. DAVENPORT.
